UNITED STATES PATENT OFFICE.

EDWARD FALES, OF WINTHROP, MASSACHUSETTS.

STOVE OR FURNACE.

SPECIFICATION forming part of Letters Patent No. 505,453, dated September 26, 1893.

Application filed June 25, 1892. Renewed August 17, 1893. Serial No. 483,413. (No model.)

To all whom it may concern:

Be it known that I, EDWARD FALES, of Winthrop, county of Suffolk, State of Massachusetts, have invented an Improvement in Stoves or Furnaces, of which the following description, in connection with the accompanying drawings, is a specification, like letters on the drawings representing like parts.

This invention has for its object to improve the construction of stoves, furnaces, or other heating apparatuses, whereby the smoke is chiefly consumed or freed from the heavy floating particles which tend to blacken it, thereby producing a white smoke, yet permitting the use of bituminous or soft coal, and furthermore saving a large percentage of the fuel.

In accordance with this invention vertical passages or flues are formed upon the inside of the rear wall of the fire pot or chamber, or if said fire pot is made circular, said vertical passages may be formed upon more or less of the interior thereof, and a smoke consuming chamber is located above the fire pot having a series of small passages communicating with and forming a continuation of the vertical passages or flues in the fire pot. The vertical passages in the fire pot serve as guide passages or flues for the flame and products of combustion, conducting them to the contracted passages in the smoke consuming chamber, and as the passages in said chamber are very small the entrances thereto will be filled or choked with the flame, and the heavy particles of coal will be burned. To break up the continuity of the vertical passages in the fire pot and smoke consuming chamber, and thereby retard the progress of the flame and the products of combustion, by turning them from a direct course, I have formed horizontal partitions in said guide passages just below the entrances to the passages in the smoke consuming chamber.

Figure 1, shows in front elevation a heating apparatus embodying this invention, the front wall being broken away to expose the part within; Fig. 2, a vertical section of the heating apparatus shown in Fig. 1, taken on the dotted line $x-x$; Fig. 3, a top view of the heating apparatus shown in Fig. 1, the top plates being removed or broken away to ex-

pose the parts beneath; Fig. 4, a modification showing a circular heating apparatus embodying this invention, and Fig. 5, a detail showing a dumping grate which may be used.

The grate herein shown is flat, and in Figs. 1, to 3, is represented as substantially rectangular, comprising several parallel fingers or bars a , formed integral with or attached to the back or rear wall b , and above said fingers or bars and extending for quite a distance parallel ribs c , are formed on said back or rear wall, the open spaces between said ribs presenting unobstructed flues or vents for the upward passage of currents of air and for guiding the flame and products of combustion. The lower part of the ribbed portion of the said rear wall b , serves as the rear wall of the fire pot or chamber containing the bed of coal. The rear wall b , extends below the grate a , and serves as the rear wall of the ash pit, which is provided with a suitable door d , having a register or draft controller.

The fire pot or chamber containing the bed of coal has suitable side walls, a front wall, and a top wall, the latter e , being connected to a suitable plate e' , extending parallel to the rear wall b , and resting upon the ribs c , so that above and at one side of the top wall e , for a short distance, the flues or vents are closed on all sides to present a thin smoke consuming chamber having small passages or flues, communicating with or forming continuations of the guide passages of the fire pot. The vertical plate e' , and rear wall b , are connected by narrow side walls, and a top e^2 , and as the ribs c , do not extend but about half way up said plate e' , a narrow chamber is formed above the ribs to which the smoke pipes f , f , are connected, said pipes terminating in a single pipe f^2 . Small horizontal partition walls g , are or may be placed in the spaces between the ribs c , at a point a little below the entrance to the passages of the smoke consuming chamber, to direct the course of the currents of air or flame or products of combustion, or break the straight continuous passages. The ribs c , terminate at the lower end at the grate a , the spaces between them communicating with the ash pit, and the door d , being provided with a suitable register permitting the entrance of a cur-

rent of air, the latter passes up through the said spaces between the ribs which serve as the flues or vents. These currents of air striking the partitions *g*, are diverted from 5 their straight onward course and are directed into the chamber, after which they pass up through the small flues or vents in the smoke consuming chamber, and then to the smoke pipes. If the partition walls *g*, are omitted 10 the said currents of air will take a more direct course, but the result is substantially the same. In either case the white smoke is carried up free from the heavy foreign particles which tend to blacken it, said particles falling 15 or being driven back on to the bed of coal to be consumed.

The top wall *e*, of the fire box is provided with suitable lids.

A rock shaft *h*, is mounted in the sides of 20 the ash pit beneath the lower ends of the ribs *c*, to which shaft a series of fingers *h*², are secured which are arranged opposite the spaces between the ribs, so that when turned into vertical position the lower ends of the flues 25 or vents will be closed. The hand lever *h*², is provided for turning said shaft. This latter device is provided for retarding the combustion when desired, and when said flues or vents are closed the currents of air will pass 30 up through the bed of coal, but when said flues or vents are open the currents of air will pass up through them instead of through the bed of coal owing to the course being the one of least resistance, although there will 35 be a very slight draft up through the bed of coal.

On the rear side of the rear wall *b*, an air chamber *i*, is formed which is open at the bottom and top to allow the cold air near the 40 floor to ascend, thereby assisting in heating the room, as well as creating a circulation of air therein, or as it is obvious the inlet may be connected with a cold air box or chute.

The grate *g*, instead of being formed integral with or secured to the rear wall *b*, as 45 shown in Figs. 1, to 3, may be secured to a rock shaft as represented in Fig. 5, in order that it may be dumped, or shaken.

Referring to Fig. 4, the fire pot or chamber 50 containing the bed of coal is made circular, and the grate bars *g*, may be forked if desired, and the ribs *c*, are arranged vertically on the rear wall which in this instance is made cylindrical, thereby presenting a central air chamber within it, which has an inlet at the bottom and an outlet at the top. In this instance several doors *d*, will be provided, at different parts of the ash pit, and also several lids at different parts of the fire 55 box.

It will be seen that my invention is susceptible of many modifications which come

within the spirit and scope of my invention.

It is obvious that the rear ribbed wall may be made in sections secured together and so 65 also the other parts of the heating apparatus.

I claim—

1. In a stove or other heating apparatus, a fire pot or chamber comprising a vertical front wall, side walls, and a rear wall, the latter 70 having upon its inside a series of parallel vertical ribs *c*, combined with the thin smoke consuming chamber rising from said fire pot, having a series of small flues or passages communicating with and forming continuations 75 of the spaces between the ribs *c*, substantially as described.

2. In a stove or other heating apparatus, a fire pot or chamber, the rear wall of which has a series of vertical ribs *c*, to present guide 80 passages or flues for the flame and products of combustion, combined with a thin smoke consuming chamber rising from said fire pot directly above the guide passages or flues formed in its rear side wall, and having a series of small passages communicating with and forming continuations of said guide passages or flues, substantially as described.

3. In a stove or other heating apparatus, a fire pot or chamber, the rear wall of which 90 has a series of vertical ribs *c*, to present guide passages or flues for the flame and products of combustion, combined with the thin smoke consuming chamber or flue comprising the ribbed rear wall, which is a continuation of 95 the ribbed rear wall of the fire pot, and the vertical plate upon the ribs of said rear wall to thereby present passages communicating with and forming continuations of the guide passages in the fire pot, substantially as described.

4. In a stove or other heating apparatus, a fire pot or chamber, the rear wall of which has a series of vertical ribs *c*, to present guide 100 passages or flues for the flame and products of combustion, combined with the thin smoke consuming chamber rising from said fire pot directly above the guide passages or flues formed in the rear side wall, and having a series of small passages communicating with 105 and forming a continuation of said guide passages or flues, and horizontal partitions located in said guide passages below the entrances to the flues of the smoke consuming chamber, thereby breaking up their continuity, substantially as described.

In testimony whereof I have signed my name to this specification in the presence of two subscribing witnesses.

EDWARD FALES.
